LOOP-CUTTING ATTACHMENT FOR RIB-KNITTING MACHINES

Charles Edwin Spicher, Millersburg, and Frank Wells Robinson, Reading, Pa.

Application May 17, 1937, Serial No. 142,960

7 Claims. (Cl. 66—147)

This invention relates to machine attachments for circular rib-knitting machines, and more particularly to loop-engaging and severing devices automatically operative to enter and cut opposite-end loops of special removable courses ordinarily introduced to unite the succession of separable fabric lengths into the usual continuously knitted tube commonly produced on these machines.

Such ribbed fabric is employed in known manner as tops for half-hose, or cuffs or the like for other articles, and each fabric section therefore commonly is knitted with a finishing course at one end formed of selvage loops, with which the loops of the special removable section-uniting courses are ordinarily engaged; and the means employed heretofore to separate the tubular sections has been to hand-cut the loops of these special courses so they may be pulled out, such additional operation adding to the cost of production and requiring nicety and skill to avoid unintentionally cutting loops of other courses and thus damaging or spoiling one or both of the united sections.

The primary objects of the present invention are to eliminate the time and cost of the aforesaid loop hand-cutting operations with their inherent irregularities and possibilities of damaging errors, by providing a simple and effective machine attachment for such purpose, and automatically operating the same to positively and accurately engage similar end loops of the respective special section-uniting courses, and sever the same, for their later ready pulling-out removal and facilitate a quick and equalized accuracy in separating the continuously knitted tube into its respective fabric sections with undamaged and more perfect courses at their free ends.

With the above primary objects in view, and with others that will later herein appear, the present invention comprises the improved loop-engaging device and cutting means, with the mechanism for automatically operating the same, as more fully described in the following specification, in connection with the drawing accompanying the same and forming part thereof, and the novel features of which are set forth in the appended claims.

Fig. 1 is a diagrammatic sectional elevation indicating the cylinder and dial, with their respective needles, of a usual circular rib-knitting machine, showing a preferred embodiment of the present improved attachment and its operating mechanism applied thereto.

Fig. 2 is a separate front elevation of the improved device alone, looking in the direction of arrow 2 of Fig. 1.

Fig. 3 is a diagrammatic showing of a fragmentary length of a continuously knitted tube, 5 indicating the usual course of special loops removably uniting the ends of two separable fabric sections.

Fig. 4 is a diagrammatic plan view indicating how the loops of the special uniting course may be engaged preparatory to their being automatically cut.

Figs. 5 and 6 are respectively front and side elevations showing a modified construction of the attachment.

Circular rib-knitting machines are old in the art and their operation is well understood, and the drawing shows only the cylinder 1 and dial plate 2 with their respective circles of cylinder needles 3 and dial needles 4, it being understood that these are operated in usual and known manner by suitable operative and pattern-control mechanism not forming part of the present invention and therefore not necessary to show. And the continuous rib-knitted tubular fabric 25 of separable fabric sections producable on such machine is also well known, and the "French Welt," indicated in the drawing, is one in common use, and is made up of similar like fabric sections 5, separably united by "pulling courses" 30 6 interengaging an end regular rib-loop course 7 of one section and a selvage-loop course 8 of the next section. Each section may have a "topping course" 9, for transfer to the needles of another machine knitting, where the separated sections are to be used as ribbed tops for half hose, and the uniting course 6, as diagrammatically indicated in Fig. 4, is usually formed of dial needle loops 10 only, the cylinder needles drawing loop bends 11, which are not knitted and cause loose longer loops in each course 6 to permit ready removal as heretofore to separate the several sections, all of which is old and well-known.

The separation of the fabric sections heretofore has required a hand-cutting of the opposite end loops of the courses 6 to free them for pulling out or removing them, such cutting requiring nicety and care and greatly reducing the speed of separating the sections, thus adding to the production cost. The present improvements, as before stated, relate to a machine attachment automatically operated to cut such end loops of the courses 6 during the knitting operation, to eliminate the hand cutting and insure a

quicker pulling out of the cut courses and more perfect separation of the sections at less cost.

Figs. 1 and 2 disclose one embodiment of the invention and show a loop-engaging finger 15 carried axially close to the inner wall of the knitting cylinder 1, with its upper, preferably hooked, end 16 adjacent the hooks of needles 3 and 4, and its lower end supported by a rod 17 shown as having a reduced extension 18 projecting through a bearing plate 19 secured to the under face of cylinder 1. Vertical movement is shown as imparted to the finger 15, by an arm 190 fixedly pivoted at 20 and pivotally connected at 21 to extension 18, with a spring 22 seating against bearing 19 and a collar 23 on extension 18 to normally hold finger 15 in its lowermost position, while permitting its vertical movement. And intermittent movement of finger 15 is provided, as shown, by a cam disc 25, having lever engageable projections 26, and carried on a shaft 27, which may be part of, or operatively connected to the machine pattern control mechanism, so the disc 25 will be rotated intermittently and in timed relation to the knitting operation.

The preferably hooked end 16 normally lies below the needles 3 and 4 in idle position, and the knitted tubular fabric, diagrammatically indicated in vertical section in Fig. 1 by reference 30, depends and is drawn outwardly through the bottom of cylinder 1 as heretofore. When the knitting of the course of loops 6 is to be made, the pattern control mechanism operates to rotate disc 25 which causes a disc projection 26 to swing arm 190 to lift finger 15, so as to position its end 16 directly behind the hook of a cylinder needle 3, and the bend of thread 11 drawn by said needle then falls over the end 16 when freed from the needle. End 16 remains in such raised position, or may be re-raised by a second projection 26, to engage in like manner a similar thread bend 11 in the same wale of the next course, and the wale loop of successive courses thus engaged remain on finger 15 and are carried downwardly thereon as the knitting progresses. In this Fig. 1 showing the finger 15 is shown with a notch forming one cutting edge 31 cooperating with a fixed cutting edge 32 on plate 33 secured to bearing plate 19, the action being that as the loops ride down finger 15 they will enter the notch and will be severed by the cutting edges 31 and 32, the proper movement of finger 15 for this cutting being effected by a suitable projection on disc 25, which may be a projection 26 or an added one similar thereto. The loops of the courses 6, of which there may be more than one uniting two sections, engage and tie the tube to said finger 15 until their loops are severed when the tube is free to be carried below cylinder 1; and disc 25 is shown with a number of projections which may act intermittently when the courses 6 are being knitted, so the finger end 16 will positively engage loops in two courses of the same wale and these loops when cut insure the freeing for pulling out of such course. By providing disc 27 with a plurality of projections like 26, as shown, finger 15 may be repeatedly moved reciprocatingly and thus insure positive loop engagement and cutting, and such finger movements will be idle except for engaging special loops dropped by the cylinder needles.

The above described embodiment may be varied, if desired, and in Figs. 5 and 6, the finger 15', operated in manner like finger 15, but having a simplified mounting by projecting the finger itself through bearing 19', is shown with sharpened

side edges 15a, 15b, which directly act to cut the loops, due to the up-and-down movement of the finger 15', as effected by projection 26', supplemented if desired by additional projections, to insure positive loop cutting by such finger movement.

From the foregoing description, the nature and operation of the present improvements will be readily understood. Their automatic operation performs a new, useful, and cost-saving operation heretofore requiring hand cutting with its inherent uncertainties, errors, and slower results. And the embodiment shown and described may of course be varied and modified within the scope of the invention as defined in the following claims. 15

We claim:

1. In a knitting machine having thread feeding and knitting mechanism for producing a succession of tubular fabric sections formed with a connecting course of special pull-out loops; automatically operated loop-engaging means for receiving opposite end loops of the pull-out courses and for severing the same so as to permit removal of said pull-out courses for separation of the fabric sections. 20

2. In a knitting machine having thread feeding and knitting mechanism for producing a succession of tubular fabric sections formed with a connecting course of special pull-out loops; automatic loop-engaging means intermittently operated to receive opposite end loops of the pull-out courses, and cutting means for severing said end loops so as to permit removal of said pull-out courses for separation of the fabric sections. 30

3. In a knitting machine having thread feeding and knitting mechanism for producing a succession of tubular fabric sections formed with a connecting course of special pull-out loops; automatic means comprising a guide finger intermittently movable to position to receive and engage opposite end loops of the pull-out courses, and cutting means for severing said end loops so as to permit removal of said pull-out courses for separation of the fabric sections. 35

4. In a knitting machine having a cylinder and dial, cylinder and dial needles, and thread feeding and knitting mechanism for producing a succession of tubular rib-knitted fabric sections formed with a connecting course of special pull-out needle loops; a guide finger mounted within said cylinder and intermittently operated to receive and engage opposite end loops of said pull-out courses, and for severing said end loops so as to permit removal of said pull-out courses for separation of the fabric sections. 40

5. In a knitting machine having a cylinder and dial, cylinder and dial needles, and thread feeding and knitting mechanism for producing a succession of tubular rib-knitted fabric sections formed with a connecting course of special pull-out needle loops; a guide finger movably mounted in said cylinder, cutting means mounted on said finger, and pattern mechanism for intermittently moving said finger to position for engaging opposite end loops of said pull-out courses, and for operating said cutting means for severing said finger engaged loops so as to permit removal of said pull-out courses for separation of the fabric sections. 50

6. In a knitting machine having a cylinder and dial, cylinder and dial needles, and thread feeding and knitting mechanism for producing a succession of tubular rib-knitted fabric sections formed with a connecting course of special pull-out needle loops; a guide finger movably mounted in said cylinder, a notch on said finger having a cutting 55

70

- edge, a separate cutting edge cooperative with said finger cutting edge, pattern control mechanism for intermittently moving said finger to position for engaging opposite end loops of said pull out courses, and pattern control mechanism for relatively moving said cutting edges cooperatively to sever said finger engaged loops to permit removal of said pull-out courses for separation of the fabric sections.
- 5 7. In a knitting machine having a cylinder and dial, cylinder and dial needles, and thread feeding and knitting mechanism for producing a succe-

sion of tubular rib knitted fabric sections formed with a connecting course of special pull-out needle loops; a guide finger movably mounted in said cylinder and having side cutting edges, pattern mechanism for intermittently moving said finger to position for engaging end loops of said pull out courses, and means for reciprocatively moving said finger to cause its side cutting edges to sever the loops engaged on said finger.
